(57) **CLAIM**

The ornamental design for an equipment support pad, as shown and described.

DESCRIPTION

FIG. 1 is a top perspective view of the equipment support pad showing our new design.

FIG. 2 is a bottom perspective view of the equipment support pad showing our new design.

FIG. 3 is a bottom plan view thereof.

FIG. 4 is a top plan view thereof.

FIG. 5 is a front elevation view thereof; the rear elevation view being a mirror image thereof; and,

FIG. 6 is a left side elevation view thereof; the right side elevation being a mirror image.

The features depicted in broken lines form no part of the claimed invention.

1 Claim, 5 Drawing Sheets
